UNITED STATES PATENT OFFICE.

GEORGE P. BOSWORTH, OF CENTRAL FALLS, RHODE ISLAND, ASSIGNOR TO HEMPHILL COMPANY, OF CENTRAL FALLS, RHODE ISLAND, A CORPORATION OF MASSACHUSETTS.

SPLICING MECHANISM FOR KNITTING MACHINES.

Original application filed December 20, 1918, Serial No. 267,707. Divided and this application filed February 9, 1923. Serial No. 618,104.

This application is a division of my co-pending application Serial No. 267,707, filed December 20, 1918, Patent No. 1,448,653, March 13, 1923.

5 This invention relates to knitting machines and more particularly to means for introducing a splicing or reinforcing yarn. Herein I have disclosed my invention in connection with the knitting of hosiery, but obviously 10 my invention is not limited thereto.

In order that the principle of the invention may readily be understood, I have disclosed a single embodiment thereof in the accompanying drawings, wherein—

15 Fig. 1 is an end elevation of a knitting machine having my invention applied thereto; Fig. 2 is a rear elevation of said machine; Fig. 3 is a plan view of the machine shown in Figs. 1 and 2; and

20 Fig. 4 is a front elevation of the upper part of a knitting machine embodying my invention.

My invention may be embodied in various types of knitting machines, whether straight 25 or circular, and whether the needles be of the spring beard or latch type. I have herein represented my invention as embodied in a circular knitting machine wherein the needles are of the spring beard type and are carried 30 by a needle cylinder to which movements of rotation and reciprocation are given in the well known manner to effect the formation of hosiery. Obviously the invention may be embodied in the knitting of hand coverings or 35 underwear.

Referring more particularly to the drawings, the frame of the machine is indicated at 1. Therein is mounted the usual drive shaft 2 having fast thereon a pinion 3 meshing with 40 a gear 4 upon the shaft 5 which also has fast thereon a cam plate or disk 6 having elevations 7 and depressions 8 of any suitable number, and herein four of each, because of the timing between the cam plate and the head. 45 The drive shaft 2 is provided with the usual pulleys 9, 10 and 11 which may be respectively high speed, low speed and loose. The knitting machine is provided with the usual needle cylinder 12 wherein are mounted 50 needles that may be either latch needles or spring beard needles, but which preferably are spring beard needles. The needles are vertically reciprocated in their grooves by a

cam ring 13 carrying cams 13' of any suitable type, as, for example, of the general character shown in the patent to Hemphill, No. 933,443. The said cam ring is carried by a cam plate 55 14 which is supported by upright rods or members, one of which is indicated at 15 in Figs. 1 and 4 and which is operatively associated with the cams upon the cam shaft so that the vertical position of the cam ring may be varied in order to vary the length of the stitches. In the disclosed embodiment of my invention, movements of rotation and reciprocation are imparted to the needle cylinder, but my invention is equally applicable to a construction wherein the needle carrier or cylinder is held stationary and the cam carrier or ring is rotated and reciprocated. 60 65 70

Upwardly extending from the bed 16 of the machine is the usual post 17 upon the upper end of which is pivoted in any suitable manner a so-called latch ring or guard 18 which is herein represented as partially surrounding the circle of needles, being primarily adapted for use with spring beard needles. Obviously a complete latch or guard ring of any other suitable character may be employed. Operatively related to the needle 75 cylinder 12 is a sinker cam ring 19 of suitable character surrounding sinkers not herein shown, but which may be of any suitable type and are mounted for radial movement in the upper edge of the needle cylinder. These 80 sinkers are adapted to be moved radially by cams of any suitable character so as to operate with the needles in the formation of 85 the loops or stitches.

The said sinker cam ring 19 rests loosely 90 upon or about the upper end of the needle cylinder and is held from rotation with the needle cylinder and its needles and sinkers in any suitable manner, as, for example, by means of adjustable screws or stops 25, 26 95 tapped into ears or lugs 27, 28 carried by or formed upon the sinker cam ring. Said ears or lugs 27, 28 are spaced apart somewhat more widely than the width of the post 17 carrying the latch or guard ring 18, thus permitting 100 a certain extent of lost motion between the needle cylinder and the sinker cam ring. This lost motion is preferably provided to permit the proper positioning of the cams of the sinker ring with respect to the cams of 105 the cam ring, that is, with respect to the knit-

ting wave of the knitting needles in a manner well known and not herein necessary fully to describe.

Preferably the machine is provided with a shaft 29 which may have mounted thereon one or more pattern or cam drums not herein necessary to refer to and which in this embodiment of my invention also has fast thereon a pattern disk or drum 30 having the 10 elevations 31, 32 functioning during the formation of the leg and heel of the stocking, and the spaces 33, 34, respectively controlling the formation of the so-called high splice and the formation of the double sole.

15 The knitting machine is provided with any suitable character of yarn or thread supplying devices. Herein and referring more particularly to Fig. 3, I have represented yarn controlling levers 35, 36, 37, 38, 39 respectively supplying yarn for the high splice, the heel and toe, the so-called boot of the stocking, the upper part of the leg of the stocking, and the introduction of a plating yarn or thread.

The said levers are mounted in any suitable 25 manner, as, for example, upon a pin or stud 40 shown most clearly in Figs. 3 and 4 in bearings extending upward from the right hand end of the latch ring or guard 18 and which may be of the general character disclosed in 30 the said Hemphill Patent No. 933,443. Each of said levers is provided with an outwardly extending toe, certain of which are indicated at 42 in Fig. 4, and with which preferably cooperate suitable means tending normally to 35 move the respective levers downwardly into yarn feeding position, that is, into the lowermost position indicated in Fig. 4. Herein for the purpose I have represented a series of levers at 43, 44, 45, 46, 47 pivoted upon a pin 48 in ears 49 upon an upright 41, said levers having tapered or wedge shaped inner ends 50 adapted respectively to take under the respective thread or yarn guides or levers and to move the same downwardly into knitting 40 position under the force of the spring 51, but is moved upwardly out of action in any suitable manner as, for example, by the means shown in the said Hemphill Patent No. 933,443, and in the Hemphill Patent No. 934,969, such 55 means being herein typified by levers, one of which is indicated at 53 in Fig. 4, as pivoted upon a pin 54 in said upright 41 and having connected thereto suitable wires or rods 55 extending downwardly into operative relation 60 to a suitable cam or pattern drum upon the cam shaft 29 in a manner not herein necessary more fully to describe.

In my said co-pending application Serial No. 267,707, I have disclosed and claimed 65 means whereby the circumferential relation

of the sinker cams and therefore the radial position of the sinkers at the effective point of the knitting wave, that is to say, at the point where the yarn is taken by the descending needles, may be varied or changed for 70 any suitable purpose but especially for the purpose of permitting the introduction of a splicing or reinforcing yarn when and where the stitches are lengthened. The invention herein claimed relates particularly to 75 the introduction of a splicing or reinforcing yarn or thread, and within the scope of the invention herein claimed, the radial position of the sinkers may or may not be varied, as desired. I will, however, briefly refer to such 80 portion of the sinker position controlling means as is herein disclosed.

As herein shown, the lug or ear 28 has tapped thereinto an adjustable screw 56 as shown in Fig. 3, and with which is adapted to cooperate a cam or other abutment 57 upon a lever indicated at 60 pivotally connected at 61 to a link 62, to the lower end of which is pivoted at 63 a lever arm 64 fast upon the shaft 65 itself mounted in bearings carried by the framing of the machine. Also fast upon the shaft 65 is a lever arm 70 which extends downward into the vicinity of the cam plate or disk 6, it having a head or roll 71 adapted for engagement with the periphery of the said cam plate, and to ride upon the elevations 7 thereof or to enter the depressions 8 between said elevations. Assuming that the said lever arm 70 with the roll 71 is permitted freely to ride upon the periphery of the cam plate or disk 6, it will be evident that when the roll 71 enters one of the depressions 8, the link 62 and the lever arm 60 will be moved upward and that the abutment 57 will be moved into the path of the supplemental screw or stop 56. When, however, said roll 71 rides upon one of the elevations 7, then the abutment 57 will be withdrawn from the path of the screw or stop 56.

The effect of positioning the cam or abutment 57 as shown in Fig. 3 is, through the action of the sinkers, to draw more yarn between the needles where the yarn is taken by the needles and therefore to increase the length of the stitches, as, for example, to permit the more ready introduction of a reinforcing or strengthening yarn.

As heretofore stated, the high splice yarn lever is indicated at 35 and in Fig. 4, I have indicated said lever in its lowermost or active position. The high splicing yarn is customarily introduced at the rear of the stocking just above the heel and if desired it extends into the upper part of the heel. Inasmuch as such yarn is introduced at the rear portion only of the stocking (in the formation of the high splice) means are provided for withdrawing the yarn lever from action during a part of the knitting of each course of a series of courses, either with or without severing the 120 125 130

yarn as it is withdrawn. The yarn may be severed when withdrawn and again when introduced or it may be floated at both the points of introduction and withdrawal to be afterwards severed, or in any suitable manner, the yarn may be manipulated so as to be knitted into each of a series of courses throughout a part only of each of said courses.

10 In Fig. 4, I have represented the high splice yarn lever 35 in its lowermost or knitting position, and in said figure I have represented an intermediate position of the yarn guide, this position corresponding to the position that will be occupied by the high splice yarn lever 35 during those portions of said courses when the yarn is not being introduced, but has been severed or is being floated. I have also in said figure indicated a yarn guide in its uppermost position, this corresponding to the position that will be occupied by the high splice yarn lever 35 when said high splice yarn lever is wholly out of action.

Although I have referred specifically to the high splice yarn lever 35 as such, it will be understood that said lever also controls the introduction of the yarn for the bottom of the foot, or if desired a separate lever may be provided for such purpose.

30 While in order to move said yarn lever 35 from its lowermost or active—that is, its knitting—position shown in Fig. 4 to its momentarily inactive intermediate position shown in said figure, I may provide any suitable means, I preferably control said lever from the needle cylinder and more especially from the sinker cam ring fast upon said needle cylinder. I have, as most clearly shown in Fig. 4, provided the sinker cam ring, which is carried by the needle cylinder 12, with a cam 73 of suitable extent and having an inclined edge 74. In the movement of rotation of said needle cylinder, said cam 74 engages with and depresses a cam lever 75 which is pivoted at 76 upon the upright 41 and is provided with an arm 77, the end 78 whereof takes under the face or shoulder 79 upon the corresponding lever 53, so as to elevate the same slightly and thereby to lift the high splice yarn lever 35 into its intermediate position. It is evident that the supplementary means thus provided for elevating the high splice yarn lever 35 into its intermediate position does not interfere with the subsequent elevation of said high splice yarn lever to its highest point or position through the action of its connecting rod or wire 55.

The cam or abutment 57 may be held out of action excepting during the formation of the high splice and double sole. Herein for the purpose I have represented a lever 74' pivoted at 75' and having an arm 76', the toe 77' whereof is adapted to ride upon the elevations 31, 32, or to enter the spaces 33, 34. The opposite arm 78' of the lever normally held

elevated by a spring 78'', has pivotally connected thereto at 79' a link or rod 80, the upper end whereof is provided with a slot 80' and is pivotally connected at 81 to a lever arm 82 fast on the shaft 65. Said shaft 65 also has fast thereon a lever arm 83 to which is connected a coil spring 84, the lower end whereof is connected to a pin 85 extending from the support 86 of the rod 15. The construction is such that when the toe 77' of the lever 74' rides upon either of the projections 31, 32, then the link or rod 80 is moved downwardly, thereby swinging upwardly the lever 83 and rocking the shaft 65 contraclockwise so as to elevate the roll 71 of the lever arm 70 entirely out of the path of rotation of the cam plate or disk 6. When, however, the toe 77' of the lever 74' enters one of the depressions 33, 34, the roll 71 is depressed into the path of the periphery of the cam disk or plate 6.

Thus in the construction disclosed it is only during the formation of the high splice or double sole that the cam or abutment 57 is moved into the path of the screw or stop 56, but the invention as herein claimed is not limited in this respect, being directed to the feeding mechanism which may or may not be associated with the sinker controlling mechanism.

Having thus described one illustrative embodiment of my invention, and the best mode known to me for practicing the method of my invention, I desire it to be understood that although specific terms are employed, they are used in a generic and descriptive sense, and not for purposes of limitation, the scope of the invention being set forth in the following claims.

I claim:

1. In yarn splicing mechanism for circular, hosiery knitting machines, a circular series of independently operated needles, cam means for causing all of the needles to knit in circular work at a single level, a plurality of yarn fingers pivotally mounted side by side, including a high splicing yarn finger, and each adapted to be moved automatically downward into fully operative position and to be moved automatically upward into inoperative, highest, idle position; a series of pivoted means adapted individually to engage said yarn fingers to control their movements into said fully operative and highest, idle positions, and means for positioning the high splicing yarn finger in an intermediate, inoperative position, said means comprising a cam rotatable about the axis of the knitting head, and a member mounted adjacent to said cam and to said pivoted means and adapted periodically to be engaged by said cam and to move the pivoted means for the high splicing yarn finger into the said intermediate position.

2. In yarn splicing mechanism for circular,

hosiery knitting machines, a circular series of independently operated needles, cam means for causing all of the needles to knit in circular work at a single level, a plurality of yarn fingers pivotally mounted side by side, including a high splicing yarn finger, and each adapted to be moved automatically downward into fully operative position and to be moved automatically upward into inoperative, highest, idle position; a series of pivoted means adapted individually to engage said yarn fingers to control their movements into said fully operative and highest idle positions, and means for positioning the high splicing yarn finger in an intermediate inoperative position, said means comprising a cam rotatable about the axis of the knitting head, and a lever mounted adjacent to said pivoted means and to said cam and adapted to be engaged by said cam and itself to engage the pivoted means for the high splicing yarn finger.

3. In yarn splicing mechanism for circular, hosiery knitting machines, a circular series of independently operated needles, cam means for causing all of the needles to knit in circular work at a single level, a plurality of yarn fingers pivotally mounted side by side, including a high splicing yarn finger, and each adapted to be moved automatically downward into fully operative position and to be moved automatically upward into inoperative, highest, idle position; a series of pivoted means adapted individually to engage said yarn fingers to control their movements into said fully operative and highest idle positions, and means for positioning the high splicing yarn finger in an intermediate inoperative position, said means comprising a cam upon the sinker cam ring and a lever adapted periodically to be engaged by said cam, and thereupon to lift the high splicing yarn finger into intermediate position.

4. In yarn splicing mechanism for circular hosiery knitting machines, a circular series of

independently operated needles, cam means for causing all of said needles to knit in circular and in reciprocating work, a plurality of yarn fingers pivotally mounted side by side to swing in vertical planes and including a high splicing yarn finger, a series of levers movable in vertical planes and each adapted to engage one of said yarn fingers so as to move the same into highest inoperative position or to permit the same to descend into lowest operative position, and means for moving the high splicing yarn finger into an intermediate inoperative position, comprising a cam rotatable about the axis of the knitting head, and means mounted adjacent to said cam and to the lever for the high splicing yarn finger and adapted periodically to be engaged by said cam and itself to act upon the lever for the high splicing yarn finger to lift the same into an intermediate inactive position.

5. In yarn splicing mechanism for circular, hosiery knitting machines, a circular series of independently operated needles, cam means for causing all of said needles to knit in circular and in reciprocating work, a plurality of yarn fingers pivotally mounted side by side to swing in vertical planes and including a high spliced yarn finger, a series of levers movable in vertical planes and each adapted to engage one of said yarn fingers, so as to move the same into highest inoperative position or to permit the same to descend into lowest operative position, and means for moving the high splicing yarn finger into an intermediate inoperative position, said means comprising a cam 73 upon the sinker cam ring, and a lever adapted periodically to be engaged by said cam and itself to engage the lever for the high splicing yarn guide, and thereby to lift the latter into an intermediate inactive position.

In testimony whereof, I have signed my name to this specification.

GEORGE P. BOSWORTH.
